MECHANISM FOR THREADING BEADS

Virgy E. Litterio and Malcolm T. Blease,
Providence, R. I.

Application April 14, 1949, Serial No. 87,394

16 Claims. (Cl. 223—48)

1

The present invention relates to the jewelry art, and has particular reference to a novel mechanism for threading beads on supporting strands.

The principal object of the invention is to provide a simple mechanism for automatically threading pierced beads on a supporting strand of cotton, nylon, fine wire or the like.

Another object of the invention is to provide a threading machine which has a hopper into which a large number of beads are loosely deposited, and which selectively positions the beads to be threaded on the supporting strand.

Still another object is to provide a threading machine which automatically aligns a number of beads and then successively mounts the beads on a strand terminal such as a needle or the like.

With the above and other objects and advantageous features in view, the invention consists of a novel arrangement of parts more fully disclosed in the detailed description following, in conjunction with the accompanying drawings, and more specifically defined in the claims appended thereto.

In the drawings, Fig. 1 is a side elevation of an apparatus embodying the invention;

Fig. 2 is a front view thereof;

Fig. 3 is a top plan view thereof;

Fig. 4 is an enlarged sectional detail showing the threading operation;

Fig. 5 is an enlarged detail section at the lower end of the aligning tube;

Fig. 6 is a perspective view of the gripper jaw mechanism; and

Fig. 7 is a perspective view of the agitator cam and its associated support bearing.

We have devised an apparatus which feeds beads, and particularly pearls, successively from a hopper to an aligning mechanism which successively positions the beads with their thread passages in substantially vertical relation, whereby the beads are successively passed over a threading needle and over a supporting strand.

Referring to the drawings, the novel threader 10 includes a support frame base 11 which has an upright panel 12 and drives a pulley 14 keyed to the motor shaft, and an upper and lower set of spaced support bars 15, 16 extend from the other side of the panel 12 to receive journal bars 17, 18 which have centrally located journals 19, 20, the journals 19, 20 being preferably of the split type.

An aligning tube 21 is positioned vertically in bearings in journals 19, 20, and is rotatably secured of the supporting strand 58 thereto.

2

driven at high speed by a pulley 22 keyed thereto, see Fig. 4, and connected to the pulley 14 by a belt 23, the pulley 22 being supported between the journals 19, 20. The upper end 24 of the aligning tube is inwardly beveled and extends through the lower base 25 of a conical hopper 26, the base 25 being generally cylindrical and forming a lower funnel portion for the hopper 26. The lower end 27 of the aligning tube 21 is constricted to provide a sliding movement of a bead therethrough, and the remainder of the aligning tube 21 is of slightly larger diameter, to permit a slight lateral movement of the beads as they pass down the aligning tube.

15 The base 25 of the hopper 26 has a fixed collar 28 with an upper cam lobe 29 in which the aligning tube is rotatably supported, and a cylindrical agitator 30, see Fig. 7, is loosely seated on the collar 28 in concentric relation to the aligning tube, the agitator having a lower cam end 31 which tilts the agitator against the aligning tube, and which intermittently contacts the cam lobe 29, whereby rotation of the aligning tube induces a slow turning and an intermittent reciprocation 20 of the agitator; the upper end 32 of the agitator breaks up any bridging of the beads in the hopper and is inwardly beveled and to guide the pearls or beads into the aligning tube.

25 A small motor is mounted in a motor easing 33, see Fig. 1, secured to the frame base, for rotating a vertical shaft 34, and through gears 35, 36 rotating a vertical shaft 37 which has two sets of cams 38, 39 and 40, 41 keyed thereto. These cams are positioned to intermittently engage two sets of gripping lever assemblies 42, 43 and 44, 45 which are pivotally mounted in upper and lower support plates 46, 47 of a fixed frame 40. Each lever assembly has two levers 49, 50 pivotally mounted through pivot openings 51 and 52 pivot pins (not shown) to its associated support plate, the levers having jaws 53 and being connected by a pivot link 54 to swing open as shown in Fig. 6 when one lever of an assembly is engaged by its cam; spring means 55 are mounted on the support plates and press against one lever of each lever assembly to normally keep the jaws in gripping relation. One lever of each lever assembly has its jaw angularly grooved as indicated by the reference numeral 56.

30 35 A vertical threading needle 58 is normally held in the grooves 55 of the lever jaws, and has its upper end 57 extending into the constricted lower end of the aligning tube, the lower end having an eye or the like for detachable 40 45 securing of the supporting strand 58 thereto.

40 45 A vertical threading needle 58 is normally held in the grooves 55 of the lever jaws, and has its upper end 57 extending into the constricted lower end of the aligning tube, the lower end having an eye or the like for detachable 45 50 securing of the supporting strand 58 thereto.

The needle 56 is preferably positioned slightly off center, as illustrated in Fig. 5, whereby the beads which pass through the constricted lower end 27 of the aligning tube shift the needle to provide an oscillation, the adjustment being preferably secured by shifting the motor casing 33.

The lever assemblies are so positioned and the lever operating cams are so timed, that the beads stack up on the needle above the upper lever assembly; the cam 37 is operated to open the upper lever assembly 41, whereupon a predetermined number of beads may pass between the lever jaws to seat on the next lever assembly 42. These beads are permitted to drop to the third lever assembly 43 upon operating movement of the cam 38, and to pass through the lower lever assemblies in due course in response to movement of the cams 39, 40, the needle 56 being always held in threading position by three of the lever assemblies.

Referring now to Fig. 4, the beads in the hopper are kept moving by the agitator and fall into the rotating aligning tube, wherein they shift laterally under the action of centrifugal force to finally turn and bring the threading passage to a substantially vertical position at the constricted outlet and to thread upon the upwardly extending off center point of the needle, whereupon they successively pass through the gripping jaw assemblies to thread upon the supporting strand.

Although we have described a specific embodiment of our invention, it is obvious that changes in the size, shape, and arrangement of parts to meet different requirements for threading beads, and to utilize a turret arrangement for threading beads of different sizes on the same supporting strand, may be made without departing from the spirit and the scope of the invention as defined in the appended claims.

We claim:

1. In a bead threading machine, a hopper adapted to receive a number of pierced beads, a bead aligning tube, guide means interposed between the hopper and the tube for guiding beads in sequence from the hopper to the upper end of the tube, means cooperating with the tube for aligning the beads in said tube with their piercings in substantially vertical position, and means detachably mounting a needle in bead-threading relation to the lower end of the tube to receive the aligned beads thereon.

2. In a bead threading machine, a hopper adapted to receive a number of pierced beads, a bead aligning tube, guide means interposed between the hopper and the tube for guiding beads in sequence from the hopper to the upper end of the tube, means cooperating with the tube for rotating the aligning tube to centrifugally align the beads in said tube with their piercings in substantially vertical position, and means detachably mounting a needle in bead-threading relation to the lower end of the tube to receive the aligned beads thereon.

3. In a bead threading machine, a hopper adapted to receive a number of pierced beads, a bead aligning tube, guide means interposed between the hopper and the tube for guiding beads in sequence from the hopper to the upper end of the tube, means for periodically agitating the beads in the hopper, means cooperating with the tube for aligning the beads in said

tube with their piercings in substantially vertical position, and means detachably mounting a needle in bead-threading relation to the lower end of the tube to receive the aligned beads thereon.

4. In a bead threading machine, a hopper adapted to receive a number of pierced beads, an elongated aligning tube, guide means interposed between the hopper and the tube for guiding beads in sequence from the hopper to the upper end of the tube, means cooperating with the tube for aligning the beads in said tube with their piercings in substantially vertical position, and means detachably mounting a needle in bead-threading relation to the lower end of the tube to receive the aligned beads thereon.

5. In a bead threading machine, a hopper adapted to receive a number of pierced beads, an elongated bead aligning tube, guide means interposed between the hopper and the tube for guiding beads, in sequence from the hopper to the upper end of the tube, means cooperating with the tube for rotating the aligning tube to centrifugally align the beads in said tube with their piercings in substantially vertical position, and means detachably mounting a needle in bead-threading relation to the lower end of the tube to receive the aligned beads thereon.

6. In a bead threading machine, a hopper adapted to receive a number of pierced beads, an elongated bead aligning tube, guide means interposed between the hopper and the tube for guiding beads in sequence from the hopper to the upper end of the tube, means for periodically agitating the beads in the hopper, means cooperating with the tube for aligning the beads in said tube with their piercings in substantially vertical position, and means detachably mounting a needle in bead-threading relation to the lower end of the tube to receive the aligned beads thereon.

7. In a bead threading machine, a hopper adapted to receive a number of pierced beads, an elongated aligning tube, guide means interposed between the hopper and the tube for guiding beads in sequence from the hopper to the upper end of the tube, means cooperating with the tube for aligning the beads in said tube with their piercings in substantially vertical position, and means detachably mounting a needle in bead-threading relation to the lower end of the tube to receive the aligned beads thereon, said thread needle mounting means positioning the thread needle point within the aligning tube and off center with respect to the tube axis.

8. In a bead threading machine, a hopper adapted to receive a number of pierced beads, an elongated aligning tube, guide means interposed between the hopper and the tube for guiding beads in sequence from the hopper to the upper end of the tube, means cooperating with the tube for rotating the aligning tube to centrifugally align the beads in said tube with their piercings in substantially vertical position, and means detachably mounting a needle in bead-threading relation to the lower end of the tube to receive the aligned beads thereon, said thread needle mounting means positioning the thread needle point within the aligning tube and off center with respect to the tube axis.

9. In a bead threading machine, a hopper adapted to receive a number of pierced beads, an elongated aligning tube, guide means interposed between the hopper and the tube for guid-

ing beads in sequence from the hopper to the upper end of the tube, means for periodically agitating the beads in the hopper, means cooperating with the tube for rotating the aligning tube to centrifugally align the beads in said tube with their piercings in substantially vertical position, and means detachably mounting a needle in bead-threading relation to the lower end of the tube to receive the aligned beads thereon, said thread needle mounting means position the thread needle point within the aligning tube and off center with respect to the tube axis.

10. In a bead threading machine, a hopper adapted to receive a number of pierced beads, a bead aligning tube, guide means interposed between the hopper and the tube for guiding beads in sequence from the hopper to the upper end of the tube, means cooperating with the tube for aligning the beads in said tube with their piercings in substantially vertical position, and means detachably mounting a needle in bead-threading relation to the lower end of the tube to receive the aligned beads thereon, said thread needle mounting means including mechanism for successively passing the beads along the needle.

11. In a bead threading machine, a hopper adapted to receive a number of pierced beads, a bead aligning tube, guide means interposed between the hopper and the tube for guiding beads in sequence from the hopper to the upper end of the tube, means cooperating with the tube for rotating the aligning tube to centrifugally align the beads in said tube with their piercings in substantially vertical position, and means detachably mounting a needle in bead-threading relation to the lower end of the tube to receive the aligned beads thereon, said thread needle mounting means including mechanism for successively passing the beads along the needle.

12. In a bead threading machine, a hopper adapted to receive a number of pierced beads, a bead aligning tube, guide means interposed between the hopper and the tube for guiding beads in sequence from the hopper to the upper end of the tube, means cooperating with the tube for periodically agitating the beads in the hopper, means for rotating the aligning tube to centrifugally align the beads in said tube with their piercings in substantially vertical position, and means detachably mounting a needle in bead-threading relation to the lower end of the tube to receive the aligned beads thereon, said thread needle mounting means including mechanism for successively passing the beads along the needle.

13. In a bead threading machine, a hopper adapted to receive a number of pierced beads, an elongated bead aligning tube, guide means interposed between the hopper and the tube for guiding beads in sequence from the hopper to the upper end of the tube, means cooperating with

the tube for aligning the beads in said tube with their piercings in substantially vertical position, and means detachably mounting a needle in bead-threading relation to the lower end of the tube to receive the aligned beads thereon, said thread needle mounting means including mechanism for successively passing the beads along the needle.

14. In a bead threading machine, a hopper adapted to receive a number of pierced beads, an elongated bead aligning tube, guide means interposed between the hopper and the tube for guiding beads in sequence from the hopper to the upper end of the tube, means cooperating with the tube for rotating the aligning tube to centrifugally align the beads in said tube with their piercings in substantially vertical position, and means detachably mounting a needle in bead-threading relation to the lower end of the tube to receive the aligned beads thereon, said thread needle mounting means including mechanism for successively passing the beads along the needle.

15. In a bead threading machine, a hopper adapted to receive a number of pierced beads, an elongated bead aligning tube, guide means interposed between the hopper and the tube for periodically agitating the beads in the hopper, guide means for guiding beads in sequence from the hopper to the upper end of the tube, means cooperating with the tube for rotating the aligning tube to centrifugally align the beads in said tube with their piercings in substantially vertical position, and means for detachably mounting a needle in bead-threading relation to the lower end of the tube to receive the aligned beads thereon, said thread needle mounting means including mechanism for successively passing the beads along the needle.

16. In a bead threading machine, in combination, a hopper adapted to receive a number of pierced beads, an aligning tube, means cooperating with the tube for rotating the aligning tube to subject the beads therein to centrifugal force, whereby said beads turn to align their piercings, and a detachably mounted stationary thread needle positioned below the lower end of the aligning tube to be threadably impaled by the piercings of the beads.
